(57) **CLAIM**

The ornamental design for a flip mobile phone with transparent display, as shown and described.

DESCRIPTION

FIG. 1 is a front perspective view of a flip mobile phone with transparent display showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a front perspective view of the flip mobile phone showing transparent display part in an alternate open position;
FIG. 8 is a front view of the flip mobile phone showing the transparent display part in another alternate position;
FIG. 9 is a rear view of the flip mobile phone showing the transparent display part in an alternate position;
FIG. 10 is a left side view of the flip mobile phone showing the transparent display part in an alternate position;
FIG. 11 is a right side view of the flip mobile phone showing the transparent display part in an alternate position;
FIG. 12 is a top view of the flip mobile phone showing the transparent display part in another alternate position;
FIG. 13 is a front perspective view of the flip mobile phone showing the transparent display part in fully closed position;

FIG. 14 is a front view of the flip mobile phone showing the transparent display part in fully closed position;
FIG. 15 is a rear view of the flip mobile phone showing the transparent display part in fully closed position;
FIG. 16 is a left side view of the flip mobile phone showing the transparent display part in fully closed position;
FIG. 17 is a right side view of the flip mobile phone showing the transparent display part in fully closed position;
FIG. 18 is a front perspective view of the flip mobile phone showing the transparent display part in fully opened position
FIG. 19 is a front view of the flip mobile phone showing the transparent display part in fully opened position;
FIG. 20 is a rear view of the flip mobile phone showing the transparent display part in fully opened position;
FIG. 21 is a left side view of the flip mobile phone showing the transparent display part in fully opened position; and,
FIG. 22 is a right side view of the flip mobile phone showing the transparent display part in fully opened position.
The shade lines in the Figures show contour or transparency and not surface ornamentation.
The broken lines in the FIG. 1, 4-5, 7, 10-11, 16-18, 21-22 show portions of the flip mobile phone with transparent display which form no part of the claimed design.
